ROBERT F. MARTIN, OF NEW YORK, N. Y., ASSIGNOR TO ROBERT F. MARTIN CORPORATION, OF NEW YORK, N. Y., A CORPORATION OF NEW YORK.

WALL CONSTRUCTION AND BRICK THEREFOR.

1,380,821.

Specification of Letters Patent. Patented June 7, 1921.

Application filed June 18, 1918. Serial No. 240,373.

To all whom it may concern:

Be it known that I, ROBERT F. MARTIN, a citizen of the United States, and resident of the borough of Manhattan, in the city, 5 county, and State of New York, have invented certain new and useful Improvements in Wall Construction and Brick Therefor, of which the following is a specification.

The present invention relates to improvements in wall constructions and to an improved brick therefor, and has for an object to provide an improved form of brick which may be built into a wall in such manner as to efficiently prevent moisture from 10 penetrating the same. Although most bricks themselves are substantially moisture proof, the moisture travels through the mortar between them. To prevent complete penetration to the interior, such brick walls have 15 heretofore been coated upon their inner side with waterproofing substances, furring, etc., and various attempts have been made to produce a brick of such shape as to provide air channels and spaces therein to render them 20 inherently moistureproof when in use.

It is an object of the present invention to provide an improved form of brick which will provide, in the wall formed therefrom, an absolute barrier to the penetration of 25 moisture through the wall, and to this end I propose to provide, in one embodiment, an air space within the wall, provided with a moisture lock so disposed with relation to the mortar joints as to effectually prevent 30 communication of moisture either by direct contact, communicating surfaces, or condensation and evaporation from the outer 35 part of the wall to the inner part.

Further objects are to enable economy in 40 the use of mortar, do away with special and unfamiliar methods of applying the mortar as are required with certain other bricks designed with a view to prevent penetration of moisture, and to provide one or more air 45 spaces permitting free circulation of air throughout the wall.

With these and other objects in view, an embodiment of my invention is shown in the accompanying drawings, and this embodiment will be hereinafter more fully described with reference thereto, and the invention will be finally pointed out in the 50 claims.

In the accompanying drawings:
55 Figure 1 is a perspective view of a section

of wall formed from an embodiment of my improved brick;

Fig. 2 is an end view of one of the bricks;

Fig. 3 is an end view of two of the bricks, superimposed, and joined by mortar; and 60

Figs. 4 and 5 are side and end views respectively of several adjacent brick, showing the bricks inclined as in the case of a wall not built level, these views being exaggerated. 65

Similar reference characters indicate corresponding parts throughout the several figures of the drawings.

Referring to the drawings, and more particularly to Figs. 1 to 3 thereof, the brick according to the present embodiment comprises a pair of spaced front and rear hollow brick sections 10 and 11 substantially corresponding in size to a regulation brick, and connected intermediately their interior adjacent faces by a lateral web 12, and provided centrally and at its upper and lower sides with longitudinal vertically disposed flanges or ribs 13 and 14, the longitudinal edges of which are flush with the upper and lower surfaces of the sections 10 and 11, and these ribs 13 and 14 do not receive mortar. 75

The structure of the brick enables the same to be manufactured by simple processes, the same being formed continuously by forcing through a die as is usual in the forming of ordinary bricks. The same may be of the length shown, that is to provide an exposed face corresponding to bricks, or "stretchers," and they may be formed in 80 half lengths or "headers" as shown in the top layer, Fig. 1, to enable various styles of bricklaying to be conveniently carried out, as for instance, Flemish bond, English bond, 85 American bond, etc.

The brick is laid as shown in Fig. 1, courses of mortar being placed upon the upper surfaces of the hollow brick mortar receiving sections 10 and 11, and carried 90 between the ends of the bricks. By placing the mortar courses toward the outer surfaces of the sections 10 and 11, no mortar will be forced into the air space, but on the other hand, by so regulating the amount of mortar and the pressure exerted upon the 95 brick laid therein, the mortar may be forced just to the air space, but will not fall therein. In the absence of the flanges 13 and 14, this falling of mortar into the air space might form a serious objection inasmuch as 100 105 110

it would form a carrier for moisture to the outer part of the wall, or a more serious objection would result from evaporation and condensation of moisture, and the communication of the condensed moisture to the mortar joints of the inner part of the wall.

The bricks are laid up with about one quarter to three quarters inch mortar joints, so that the longitudinal and transverse edges 10 of the webs and ribs are separated an equal distance as at A and B, thus allowing for free circulation of air throughout the wall. The transverse spaces B are staggered in relation to each other, while the longitudinal channels C and D, extend above and below the mortar joints, and are separated by the opposed ribs 13 and 14.

Any moisture accumulating in the channel C, and condensing upon the upper surfaces 20 will be returned to the same channel, even though the wall be considerably inclined, as shown in Fig. 5, the drops falling from the outer surface of the flange 13, while the free circulation of air in the channels will cause the moisture to be quickly 25 evaporated. Should the wall be longitudinally inclined (Fig. 4) the moisture will travel in a stepped course along several bricks, gradually evaporating.

30 The ribs or flanges 13 and 14 form an effective barrier to the penetration of moisture to the inner wall section, and provide a large surface for condensation of moisture in the channel C, so that even though the moisture be in a vaporous state it will be 35 prevented to a large extent from entering the channels D, and finally penetrating the inner wall section.

The corners between the brick sections and 40 the web 12, and between the web 12 and the ribs 13 and 14, are preferably rounded as shown, although it will be understood that these corners may, if desired, be angular. This materially strengthens the connection 45 between the web and the brick sections, and prevents warping of the brick during treatment of the same in the brick kilns. Also, a better surface for the flow of moisture through the channels is provided.

50 It will be noted that my invention comprises an improved non-porous brick for hollow wall construction, comprising a web, a hollow brick wall supporting section at each end of the web and arranged perpendicularly to the web, and having mortar receiving surfaces the full width of the sections, non-porous water repellent and water barring ribs extending from the web in opposite directions, and terminating within 55 the confines of the space between the common plane of the upper mortar receiving surfaces of the brick wall supporting sections and the common plane of the lower mortar receiving surfaces thereof, and terminating in non-mortar receiving surfaces,

the ends of said ribs being flush with the ends of the sections, and the thickness of the walls of the hollow sections, and web and ribs being substantially equal and within kiln treatment limits, and also the combination of a plurality of bricks to form 70 an improved wall construction consisting of a double wall structure, comprising a plurality of superimposed courses of matched bricks, each brick comprising spaced hollow 75 brick wall supporting sections forming the double wall, the upper and lower surfaces of the sections being relatively wide and constituting bearing surfaces adapted to receive mortar therebetween to the full width 80 of the bearing surfaces to space and join the superimposed bricks, a longitudinal web extending laterally between and connecting said hollow brick sections, longitudinal ribs extending from each side of said web intermediate the longitudinal edges thereof, at the top and at the bottom of the brick and terminating in the common planes of the mortar receiving surfaces, the facing edges 85 of said ribs being non-mortar receiving and spaced from the ribs of adjacent bricks by a distance corresponding to the mortar on the bearing surfaces between said adjacent 90 brick sections, the ends of the ribs being flush with the ends of the sections but being 95 non-mortar receiving, to provide intercommunication and circulation of air throughout the space between abutting bricks and between the facing edges of said ribs, and obstructing the transverse conduction of 100 moisture from one brick section to another, and the thickness of the walls of the hollow sections, web and ribs being substantially 105 equal and within kiln treatment limits, and an additional improvement thereover in the coöperation of the hollow section circulation with the circulations above mentioned.

In firing brick in a kiln, the hollow bricks are stood on end so as to allow the heat to circulate, and keep the brick from crushing 110 under its own weight while burning, and also, as it is impossible to provide circulation of heat from side to side, all brick kilns have an up and down draft circulation. The brick of the present invention is especially 115 suited to this treatment, the ends of the hollow brick wall supporting sections and the webs and ribs being flush so that as the webs and ribs are supported during firing, and as they are within kiln treatment limits, 120 the same will not become warped or displaced.

As no twisting or warping results from the processes of manufacturing, the brick will be such that it will lay plumb and level 125 in the wall. The mortar receiving surfaces are flat and are bedded in a flat mortar surface so that any pebbles therein will show and can be thrown out with the point of the trowel.

I have illustrated and described a preferred and satisfactory embodiment of my invention, but it is obvious that changes may be made therein within the spirit and scope 5 thereof, as defined in the appended claims.

I claim:—

1. A double wall structure, comprising a plurality of superimposed courses of matched bricks, each brick comprising spaced 10 hollow brick wall supporting sections forming the double wall, the upper and lower surfaces of the sections being relatively wide and constituting bearing surfaces adapted to receive mortar therebetween to the full width 15 of the bearing surfaces to space and join the superimposed bricks, a longitudinal web extending laterally between and connecting said hollow brick sections, longitudinal ribs extending from each side of said web 20 intermediate the longitudinal edges thereof, and terminating in the common planes of the mortar receiving surfaces at the top and at the bottom of the brick, the facing edges of 25 said ribs being non-mortar receiving and spaced from the ribs of adjacent bricks by a distance corresponding to the mortar on the bearing surfaces between said adjacent brick sections, the ends of the ribs being flush with the ends of the sections but being non-mortar 30 receiving to provide intercommunication and circulation of air throughout the space between abutting bricks and between the facing edges of said ribs, and obstructing the transverse conduction of moisture from one 35 brick section to another, and the thickness of the walls of the hollow sections, web and ribs being substantially equal and within kiln treatment limits.

2. A wall structure comprising a plurality 40 of superimposed courses of matched bricks, each brick comprising spaced hollow brick wall supporting sections forming the double wall, the upper and lower surfaces of said sections being relatively wide and constituting 45 bearing surfaces adapted to receive mortar thereon to the full width and length thereof, to space and join the superimposed bricks, the ends of said sections of longitudinally adjacent bricks adapted to be 50 spaced, a longitudinal web extending laterally between and connecting said hollow brick sections, longitudinal ribs extending from each side of said web intermediate the longitudinal edges thereof, and terminating 55 in the common planes of the mortar receiving surfaces of the top and bottom of the brick, the facing edges of said ribs being non-mortar receiving and spaced from the ribs of adjacent bricks by a distance corresponding 60 to the mortar on the bearing surfaces between said adjacent brick sections, the ends of said ribs being flush with the ends of the sections but being non-mortar receiving to provide intercommunication 65 and circulation of air throughout the space

between abutting bricks and between the facing edges of said ribs and obstructing the transverse conduction of moisture from one brick section to another, the ends of said web and ribs of longitudinally adjacent 70 bricks being non-mortar receiving and spaced from like members of abutting bricks to provide intercommunication and circulation of air throughout the space between the brick sections from end to end thereof and from side to side thereof, the hollow brick wall supporting sections coöperating to produce a circulation in coöperation with the circulations aforesaid, and the thickness 75 of the walls of the hollow sections, web and ribs being substantially equal and within 80 kiln treatment limits.

3. A building block comprising two longitudinally extending hollow load bearing sections transversely spaced from each other 85 for a distance not greater than the width of the individual sections, and non-load bearing means integrally connecting said hollow sections to each other and forming a plurality of longitudinally extending air passages in each side of the block, each passage being of a width appreciably less than the width of said hollow load-bearing sections.

4. A non-porous brick for hollow wall construction, comprising a web, a hollow 95 brick wall supporting section at each end of the web and arranged perpendicularly to the web, and having mortar receiving surfaces the full width of the sections, non-porous water repellent and water barring 100 ribs extending from the web in opposite directions, and terminating within the confines of the space between the common plane of the upper mortar receiving surfaces of the brick wall supporting sections and the 105 common plane of the lower mortar receiving surfaces of the brick wall supporting sections, and terminating in non-mortar receiving surfaces, the ends of said ribs being flush with the ends of the sections but being 110 non-mortar receiving, and the thickness of the walls of the hollow sections, web and ribs being substantially equal and within kiln treatment limits.

5. A wall structure composed of blocks, 115 each having two longitudinally extending hollow load-bearing sections transversely spaced from each other, and non-load bearing means integrally connecting said hollow sections to each other and forming a plurality of longitudinally extending air passages in each side of the block in transverse communication with each other throughout the length of the block, and also in transverse communication with the opposed passages in the blocks of adjoining courses in the wall structure.

6. In building construction, a wall structure composed of alternating courses of brick and binding material, each brick com- 130

prising transversely spaced load-bearing sections connected by a horizontal web, the binding material being disposed between the opposed side and end surfaces of the 5 load-bearing sections of the adjoining brick in the wall structure, and means on each side of said web forming a plurality of parallel open channels between said load-bearing sections, said web and channel 10 forming means of adjacent brick in the same course being separated at their ends by

an unobstructed space, and the channel forming means of vertically adjacent brick being in spaced alignment with each other, whereby said channels are in transverse communication with each other throughout the length of the individual brick and also with the channels of the horizontally and vertically adjoining bricks in the wall structure. 15

In testimony that I claim the foregoing 20 as my invention, I have signed my name.

ROBERT F. MARTIN.
